SELECTIVE RINGING TELEPHONE UNIT

Thomas J. McCann, New York, N. Y., assignor to
 Hose McCann Telephone Co., Inc., Brooklyn,
 N. Y., a corporation of New York

Application April 11, 1950, Serial No. 9,147

Term of patent 14 years

(Cl. D26—14)

To all whom it may concern:

Be it known that I, Thomas J. McCann, a citizen of the United States, residing at New York, in the county of Kings and State of New York, have invented a new, original, and ornamental Design for a Selective Ringing Telephone Unit, of which the following is a specification, reference being had to the accompanying drawing, forming part thereof.

In the drawing:

Fig. 1 is a front elevational view of a selective ringing telephone unit, showing my new design;

Fig. 2 is an elevational view of one side thereof, and

Fig. 3 is an elevational view of the other side. The cord has been fragmentarily shown for convenience of illustration.

I claim:

The ornamental design for a selective ringing telephone unit, substantially as shown and described.

THOMAS J. McCANN.
